SPARK PLUG

Ernest F. Koehler, Berlin, and Gustave W. Goerner, Bourne, Mass.

Application April 9, 1936, Serial No. 73,452

6 Claims. (Cl. 123—169)

Our invention relates to spark plugs for internal combustion engines and has for its principal object to provide an improved negative or ground electrode and means for mounting the same, so that this electrode may be readily replaced and renewed when partly burned away or distorted by use. A further object has been to provide a ground electrode which shall cause the spark to be spread and distended so that it may 10 perform its function more efficiently.

Our device may be best understood by reference to the accompanying drawing in which:

Fig. 1 is an elevation of our improved spark plug.

Fig. 2 is a vertical section through the plug of Fig. 1.

Fig. 3 shows a first modified form of our invention in which the removable ground electrode instead of being curved in an arc below the end 20 of the positive electrode, as in Fig. 1, is curved in an arc laterally disposed with respect to the end of the positive electrode; the lower part of the shell and insulator core being shown in vertical, medial cross section.

Fig. 4 is an enlarged section of the lower portion of the shell showing the grooves wherever a ground electrode may be removably mounted.

Fig. 5 shows in section the shell of Fig. 4 with the ground electrode of Figs. 1 and 2 mounted therein and the insulator core and positive electrode in place.

Fig. 6 is an enlarged cross-section on line 6—6 of Fig. 3, with the insulator core removed.

Fig. 7 is a cross-section on line 7—7 of Fig. 5 with the insulator core removed.

Fig. 8 is an enlarged section on line 8—8 of Fig. 3 with the insulator core removed.

Fig. 9 shows in cross-section corresponding to that of Fig. 6 a second modified form of our invention wherein appear two removable ground electrodes each organized and removably mounted like the other on its respective side of the end of the positive electrode.

Fig. 10 is an enlarged bottom view of the spark plug shown in Fig. 1.

Fig. 11 is a perspective view of a removable ground electrode such as is shown in Figs. 1 and 2.

Fig. 12 is a cross section corresponding to Fig. 6 showing a third modified form in which a pair of parallel removable ground electrodes are employed.

Referring now to the drawing, in which like reference numerals indicate like parts, 1 is a shell provided with an extension 2 of reduced

diameter and threaded to enter the usual threaded hole in the casing of the motor. The bore 3 of the casing 1 tapers slightly in a portion of its extent, as most clearly shown in Fig. 4, thereby providing a seat for a correspondingly tapered portion of the porcelain insulator 4. The upper part of the insulator 4 is of uniform, reduced diameter affording an annular shoulder 5 against which is seated the threaded extension of the jam nut 6 which is screwed into the threaded top of 10 the bore 3 of the casing 1, thereby pressing the tapered portion of the insulator 4 into firm engagement with the tapered portion of the bore 3 of the casing 1.

The insulator 4 is provided with a central bore 13 in which is inserted the positive electrode 7 the top of which is press-fitted into hole 8 in the base of the metal insulator cap 9 the cylindrical portion 10 of which is screw threaded to engage screw threads in the top cavity of the insulator 4. 20

A binding post 11, integral with the cap 9 is screw threaded to receive the conventional knurled binding nut 12 for attaching the high tension wire.

The interior of the threaded extension 2 of the 25 casing is provided with opposite grooves 13 which enter an annular groove 14 located immediately below the narrowest part of the tapered bore 2 of the casing 1. Within these grooves 13 and 14 is 30 removably mounted the steel wire ground electrode 15 which may be inserted in place when the insulator 4 has been removed and will be locked in place by the insulator when the insulator is returned to position as shown in Fig. 5. 35 As will be more readily understood from an examination of Fig. 11 the electrode 15 is generally re-shaped and provided with straight upwardly extending parts or legs which are slightly spread apart so that the free ends of the legs which take 40 the form of curved lateral arms 16 may, after the tops of the straight upwardly extending parts are slightly pressed together to permit insertion within the extension 2, be forced with firm spring tension into engagement with the ground part 14 of the casing 1 when the straight upwardly extending parts of the electrode 15 are entered in grooves 13 and firmly seated there.

The lower central part 17 of the ground electrode 15 is preferably given a substantially regular arc of curvature centered on the middle of 50 the tip of the positive electrode 7; and, as shown in Figs. 1, 2, 5, 7, 10 and 11, this arc of curvature may be vertically disposed beneath the tip of the electrode 7, or, as shown in Figs. 3, 6 and 8 this arc 17 may be laterally disposed with respect to 55

the tip of the ground electrode which, as shown in Fig. 3, may be slightly extended for this purpose.

In a modified form of our invention, such as 5 that shown in Fig. 9, a pair of oppositely placed ground electrodes each formed with a laterally disposed arc 17' may be employed, the arcs being oppositely positioned so as substantially to surround the end of the positive electrode 7. In 10 this form of construction the vertical grooves 18', corresponding to the grooves 18 of Fig. 6 are made wider to accommodate the pair of ground electrodes and the curved arms 18' extend toward each other instead of extending in opposite directions 15 as in Fig. 6.

A further modified form appears in Fig. 12 a pair of ground electrodes 18' each organized in the general manner heretofore described except that the vertical slots 18' wherein each is mounted 20 are not diametrically opposite each other but so arranged that the two ground electrodes 18' bridge straight across the base of the casing 1 parallel to each other and upon opposite sides 25 of the positive electrode 7 so as to form double spark gaps, and the arms 18' of each of these ground electrodes, like those shown in Fig. 6 previously described, extend toward each other.

From the foregoing description it will be 30 readily understood that our removably mounted ground electrodes may be quickly and easily replaced when they become burned out or distorted by use, and that while in place they will maintain at all times an extensive, firm, spring pressed 35 contact with the shell or casing of the plug so as to afford a good electrical connection.

The arc 17 or 17' of the ground electrodes being substantially a part of a true circle centered on the axis of the positive electrode will result in a broad, fan shaped spark giving excellent ignition; 40 and where the parallel arrangement of cross members of Fig. 12 is employed the cross members may be, if necessary, slightly pinched together and permanently distorted to compensate for the burning away of adjacent areas of the positive and ground electrodes which has too much widened the spark gaps.

Having thus fully described our invention what we claim is:

1. In a spark plug the combination of a casing 50 provided with a bore which is cylindrical at its lower end and provided with an annular groove, a ground electrode the ends of which are bent to form arcuate portions adapted to fit within and engage said groove and the central portion of which is arranged to underlie and bridge across said bore and form a spark gap between said central portion and a positive electrode, a positive electrode adapted to fit within said bore and to retain the ends of said ground electrode within said groove.

2. In a spark plug the combination of a casing 55 provided with a bore which is cylindrical at its

lower end and provided with an annular groove and with oppositely placed straight grooves communicating with said annular groove, a generally U-shape ground electrode the legs of which fit within and engage said straight grooves and the central portion of which is arranged to underlie and bridge across said bore and form a spark gap between said central portion and a positive electrode, the free ends of the legs being bent to fit within the annular groove, a positive electrode 10 and an insulator for said positive electrode adapted to fit within said bore and to retain the ends of said ground electrode within said annular groove.

3. A spark plug according to claim 1 in which 15 the central portion of the bridge between the legs of the ground electrode is bent to form an arc of a circle which is centered with respect to the end of the positive electrode, the arcuate central portion being connected to the legs by generally 20 radially disposed bridge portions.

4. In a spark plug the combination of a casing provided with a bore which is cylindrical at its lower end, a positive electrode centrally mounted in said bore, an insulator for said positive electrode, a pair of negative electrodes mounted in said casing in a manner whereby they may bridge across said bore, said electrodes lying upon opposite sides of the extremity of said positive electrode in a parallel manner, said insulator 30 maintaining said negative electrodes in proper operative spaced relation to the positive electrode.

5. In a spark plug the combination of a casing provided with a bore which is cylindrical at its lower end, a positive electrode centrally mounted 35 in said bore, an insulator for said positive electrode, there being an annular groove in the casing opening into the cylindrical bore, a pair of generally U-shape negative electrodes mounted in said casing, the free ends of the legs of each U- 40 shape electrode being bent towards one another to form arcuate portions which fit within the groove, said negative electrodes having portions which bridge the legs thereof to lie upon opposite sides of the extremity of said positive electrode in 45 oppositely extending similar arcs centered about the end of said positive electrode.

6. In a spark plug the combination of a casing having a bore which is cylindrical at its lower end and provided with a cavity opening into the 50 cylindrical bore, there being a groove in the casing extending from the cavity longitudinally of the bore to the outer end thereof, a ground electrode in the form of a wire fitted into the groove, and having an end bent to fit into said cavity, a 55 positive electrode and an insulator for said positive electrode, said insulator extending downwardly into the cylindrical bore to engage the ground electrode and prevent movement thereof in said cavity and groove.

ERNEST F. KOEHLER,
GUSTAVE W. GOERNER.
